UNITED STATES PATENT OFFICE.

ANDREAS BECKER, OF VAILSBURG, NEW JERSEY, ASSIGNOR TO BRACHER,
BECKER & BARNETT, OF NEWARK, NEW JERSEY, A FIRM.

DESIGN FOR A RING.

SPECIFICATION forming part of Design No. 36,009, dated August 19, 1902.

Application filed June 14, 1902. Serial No. 111,785. Term of patent 7 years.

To all whom it may concern:

Be it known that I, ANDREAS BECKER, a citizen of the United States, and a resident of Vailsburg, county of Essex, and State of New Jersey, have invented a new, original, and ornamental Design for a Ring, of which the following is a full, clear, and exact description.

Reference is to be had to the accompanying drawing, which is a perspective view of a ring embodying my new design.

The leading feature of my design consists

in a ring having thereon the representation of two elks, with their antlers inclosing a central space. As shown, each of the elks is represented as running through grass, and this ornamentation is carved in relief.

I claim as my invention—

The ornamental design for a ring, substantially as shown and described.

ANDREAS BECKER.
